UNITED STATES PATENT OFFICE.

LEWIS D. BLACKSHERE, OF CHARLESTON, WEST VIRGINIA, ASSIGNOR TO THE LIBBEY-
OWENS SHEET GLASS COMPANY, OF TOLEDO, OHIO, A CORPORATION OF OHIO.

SHEET-GLASS-DRAWING APPARATUS.

Application filed August 17, 1927. Serial No. 213,465.

This invention relates to improvements in sheet glass drawing apparatus. An important object of the present invention is to provide in sheet glass apparatus wherein a preferably endless drawing and flattening table is employed for drawing a sheet from a molten source, means for protecting the table during its sheet supporting run from the means used for heating the table during its return or non-sheet supporting run.

Another object of the invention is to provide in sheet glass apparatus, a preferably endless drawing and flattening table for drawing a sheet from a molten source, and means arranged between the runs of said table for insulating the sheet supporting run of the table together with the sheet carried thereby from the heating flame directed against the return or non-sheet supporting run thereof.

A further object of the invention is to provide a horizontally arranged preferably endless drawing and flattening table for drawing a sheet from a molten source, with insulating means arranged between the upper and lower runs of said table for protecting the upper run together with the sheet resting and being carried along thereupon from the blast and heat of the burners preferably used for heating the table during its lower run.

Other objects and advantages of the invention will become more apparent during the course of the following description when taken in connection with the accompanying drawings.

In the drawings forming a part of this application and wherein like numerals are employed to designate like parts throughout the same,

Fig. 1 is a longitudinal vertical section through an apparatus constructed in accordance with the present invention, and

Fig. 2 is a section taken substantially on line 2-2 of Fig. 1.

In the drawings, wherein for the purpose of illustration is shown a preferred embodiment of the present invention, the numeral 5 designates a draw pot containing a source of molten glass 6 from which is drawn a sheet 7 adapted to be deflected over a bending roll 8 and passed over a drawing and flattening table designated in its entirety by

the numeral 9. Arranged above the table 55 9 are a plurality of clamp bars 10 arranged in an endless belt formation and trained about sprockets or drums 11. These clamp bars which may or may not be used as desired extend transversely of the table 9 and are 60 arranged to engage the opposite edges only of sheet 7.

The drawing and flattening table 9 is composed of a plurality of preferably metallic links 12 connected together in a manner to form substantially an endless flexible belt which may be trained about sprockets or drums 13 and kept taut by means of an idler 14. As shown, the table 9 is horizontally arranged with its upper run supported upon 70 and passing over a plurality of closely associated longitudinally extending table rails 15 mounted upon transverse supports 16, said rails 15 being of a substantially inverted channel-shaped formation and serving to hold the upper run of the draw table in a substantially perfectly flat horizontal plane. 75

To prevent too rapid cooling of the sheet 7 as it passes over the drawing and flattening 80 table 9 it is necessary to heat the various links thereof and this is preferably accomplished by the use of burners 17 which direct flames 18 upon the table during its lower return or non-sheet supporting run. 85

It is desirable, however, that the upper sheet supporting run of table 9 together with the sheet resting thereupon be protected or insulated from the blast and heat of the burners 17 in order that the best results in 90 the drawing and flattening of the sheet may be obtained. Also, it is preferable that the flames 18 be prevented from playing directly upon the table rails 15 since this heat may tend to soften or otherwise injure the same. 95

To accomplish the above objects, suitable insulating material such as indicated at 19 may be arranged within the channel-shaped rails 15 and a heat resisting plate or slab 20 may be secured to the underside of said 100 rails. The insulating material 19 together with the slab or plate 20 may be of a suitable refractory material. With such a construction, the plate 20 and material 19 will effectively protect the upper sheet carrying 105 run of the draw table and the sheet resting thereupon from the blast and heat of the burners 17, while the plate 20 will further

serve to prevent the flames from playing upon and softening or otherwise injuring the table rails 15.

It is to be understood that the form of 5 the invention herewith shown and described is to be taken as the preferred embodiment of the same, and that various changes in the shape, size and arrangement of parts may be resorted to without departing from the 10 spirit of the invention or the scope of the subjoined claims.

Claims—

1. The combination with an endless sheet 15 glass drawing apparatus draw table, and means for heating the same, of means for protecting the sheet carrying run of said table from said heating means.

2. The combination with an endless sheet 20 glass drawing apparatus draw table having a sheet carrying run and a return run, and means for heating the table during its return run, of means for protecting the table from the heating means during its sheet supporting run.

3. The combination with an endless sheet 25 glass drawing apparatus draw table having a sheet carrying run and a return run, and means for heating said table, of insulating means arranged between the heating means 30 and sheet carrying run of the table.

4. The combination with an endless sheet 35 glass drawing apparatus draw table having a sheet carrying run and a return run, with said sheet carrying run traveling in a sub-

stantially horizontal plane, and means for 35 playing a flame upon the table during its return run, of means between the two runs of the table for protecting the sheet carrying run from said flame.

5. The combination with an endless sheet 40 glass drawing apparatus draw table having a sheet carrying run and a return run, means for supporting said sheet supporting run, and means for heating said return run, of 45 means for protecting said sheet supporting run and supporting means therefor from said heating means.

6. The combination with an endless sheet 50 glass drawing apparatus draw table having a sheet carrying run and a return run, means for supporting said sheet supporting run, and means for heating said return run, of insulating means carried by said supporting means for protecting the same together 55 with said sheet supporting run and sheet from said heating means.

7. The combination with an endless sheet 60 glass drawing apparatus draw table having a sheet carrying run and a return run, rails for supporting said sheet carrying run, and burners for heating said return run, of a heat resisting plate carried by said rails for protecting the same from the blast and heat of the burners.

Signed at Charleston, in the county of 65 Kanawha and State of West Virginia, this 12th day of August, 1927.

LEWIS D. BLACKSHERE.
